CURTAIN SUPPORT

Eugene Le Veau, New York, N. Y.

Application September 13, 1938, Serial No. 229,755

2 Claims. (Cl. 156—22)

This invention relates to a support for sliding curtains of the type wherein slides in the nature of balls or rollers are arranged in a longitudinally slotted tubular rod or pole and provided with depending hooks engageable with the upper edge of the curtain, whereby the latter is suspended for being readily drawn to one side.

The primary object of the present invention is to provide an improved curtain support of the above kind, particularly useful in suspending shower bath curtains in surrounding relation to a bathtub.

A more specific object of the present invention is to provide a curtain support of the above character, wherein simple and efficient means is provided for mounting the curtain rod and sustaining the weight of the latter and the curtain in an efficient manner, as well as providing for convenient mounting and dismounting of the curtain rod.

With the above objects in view, the present invention consists in the novel form, combination and arrangement of parts hereinafter more fully described, shown in the accompanying drawing and claimed.

In the drawing:

Figure 1 is a view, partly in front elevation and partly broken away and in section, of a curtain support constructed in accordance with the present invention and illustrated as it appears in use.

Figure 2 is a section on line 2—2 of Figure 1.

Figure 3 is an enlarged transverse section on the plane of line 3—3 of Figure 2.

Figure 4 is a fragmentary view partly in side elevation and partly in section, showing details of the mounting means illustrated in Figure 3.

Figure 5 is a section on line 5—5 of Figure 3.

Figure 6 is a section on line 6—6 of Figure 1.

Figure 7 is a view similar to Figure 3 illustrating a modified form of curtain rod.

Figure 8 is a view similar to Figure 4 of the construction shown in Figure 7.

Figure 9 is a view similar to Figure 5 of the embodiment of Figure 7; and

Figure 10 is a section on line 10—10 of Figure 9.

Referring in detail to the drawing, the present curtain support includes a suitable tubular curtain rod 5 having a slot 6 extending longitudinally therein from end to end of the same. Arranged in the tubular rod 5 are a plurality of slides 7 having depending hooks 8 or the like projecting outwardly through the slot 6 and adapted for engagement with the upper edge of the curtain 9 to be suspended. The rod 5 may

be of circular form in cross section and provided with the slot 6 at the bottom as illustrated in Figures 1 to 6 inclusive, in which case the slides 7 are in the nature of balls loosely fitting within this tubular rod 5. However, as illustrated in Figures 7 to 10 inclusive, the rod 5 may be in the nature of a vertically flattened tube having the slot 6 in one side thereof, in which case the slides 7 are in the nature of rollers arranged to ride on the lower wall of the rod and journaled upon laterally directed upper ends of the hooks 8 or the like. The rod 5 is shown of U-shape so that the curtain 9 may be suspended to depend in surrounding relation to the outer side and the ends of a bathtub as required in connection with shower bath curtains.

In accordance with the present invention, simple and efficient means is provided for effectively removably supporting the curtain rod 5 in proper position with relation to and above the bathtub. As shown, each end of the rod 5 is slidably fitted in a socket or sleeve member 10 of a mounting bracket which includes a base flange 11 apertured for reception of screws 12 or the like whereby the bracket may be securely fastened to the adjacent vertical wall at the inner side of the bathtub. Obviously, the sleeve or socket 10 will be of circular form when used in connection with the rod of Figure 1, and will be of flattened, somewhat elliptical form when used in connection with the rod of Figure 7. In order to removably secure the ends of the rod in the sockets or sleeves 10 of the respective end mounting brackets, I preferably provide headed pins 13 extending through vertical slots 14 in the socket or sleeve members 10 and provided on their outer ends with knobs 15. Also, the ends of the curtain rod are provided with bayonet slots 16 whose upper horizontal portions open through the end edges of the rod to receive the pins 13 when the rod is inserted in the sleeves or sockets 10 of the mounting bracket and when the pins 13 are disposed at the top of the slots 14. By this arrangement, the pins 13 may be lowered in the slots 14 and the inner vertical portions of the bayonet slots 16 after the ends of the rod 5 are inserted in the sockets or sleeves 10 of the mounting bracket, whereby the ends of the rod are effectively locked in said sleeves or sockets against accidental detachment. At the same time, the curtain rod may be readily dismounted by simply raising the pins 13 to the upper ends of the slots 14 and in alignment with the upper horizontal portions of the bayonet slots 16, in which case the ends of the rod may be readily drawn out of

the sleeves or sockets 18 of the mounting brackets. Of course, the slides 7 with their hooks 8 will be inserted in the rod from either or both ends thereof prior to engagement of the 5 ends of the rod into the sockets or sleeves 18 of the mounting brackets.

While the ends of the rod are effectively attached to the adjacent wall as described above, the curtain rod must be supported against sagging at a point intermediate the ends thereof 10 so as to effectively sustain the weight of the rod and the curtain suspended from the hooks 8. In order to accomplish this without in any way interfering with the movement of the slides 15 7 necessary when drawing the curtain to one side or back to its surrounding relation to the bathtub, I provide a center support consisting of an elongated member 17 in the form of a rod or chain having means 18 to attach the upper 20 end thereof to the ceiling of the room and provided at its lower end with a split clasp 19 adapted to partially embrace the rod 5 with a strong gripping engagement with the latter. The clasp 19 has the ends of its jaws spaced 25 apart adjacent but at opposite sides of the slot 8 in the rod 5 so as to not interfere in any way with movement of the slides 10 and the curtain suspended therefrom. While the clasp 19 will effectively maintain its engagement with the rod 30 in opposition to the weight of the latter and the curtain, said rod may be forcibly manually disengaged from the clasp whenever it is desired to dismount the rod and the curtain supported therefrom.

35 From the above description, it is believed that the construction as well as the advantages of the present invention, will be readily understood and appreciated by those skilled in the art. Minor changes in the specific construction and 40 embodiment illustrated and described, are contemplated within the spirit and scope of the invention as claimed. While the complete rod is not illustrated in connection with the embodiment of Figures 7 to 9 inclusive, it will be under-

stood that the same may be of general U-shape as illustrated with respect to the rod in the embodiment of Figures 1 to 6 inclusive.

What I claim as new is:

1. A quickly demountable support for sliding shower bath curtains, comprising a curtain rod of U-shape in plan providing an intermediate portion of a length substantially equal to the length of the shower bath tub and long end portions extending at right angles to said intermediate portion and of a length substantially equal to the width of said tub for supporting the curtains in surrounding relation to the ends and outer side of said tub, means to detachably mount the rod including brackets adapted to be 15 secured to a vertical wall, detachable connections between said brackets and the ends of said rod, and vertical elongated suspension means for the intermediate portion of the rod having means to attach the upper end of the same to a 20 ceiling and means to detachably engage the curtain rod at the lower end thereof.

2. In a support for sliding shower bath or like curtains, a tubular curtain rod, and means to detachably mount the ends of the rod upon a 25 vertical wall including a sleeve adapted for snug reception of the adjacent end of the rod and having an apertured attaching base flange, said sleeve being provided with a vertical elongated slot extending transversely of the axis of the 30 sleeve, a headed pin slidable in said slot and having an operating knob on its outer end, and bayonet slots in the ends of the rod opening through the end edges thereof for reception of 35 said pins when arranged at the upper ends of said vertical slots of the sleeve, the inner vertical portions of said bayonet slots being arranged to align with the vertical slots of the sleeves when the ends of the rod are inserted in said sleeves so that lowering of the headed 40 pins will effect a lock connection between the sleeves and the ends of the rod.

EUGENE LE VEAU.
